UNITED STATES PATENT OFFICE.

CHARLIE H. DOUGLASS, OF PHILADELPHIA, PENNSYLVANIA.

HOLDER FOR GRAMOPHONE DISK RECORDS.

No. 877,060.

Specification of Letters Patent.

Patented Jan. 21, 1908.

Application filed September 24, 1906. Serial No. 336,051.

To all whom it may concern:

Be it known that I, CHARLIE H. DOUGLASS, a citizen of the United States, residing at Philadelphia, county of Philadelphia, and 5 State of Pennsylvania, have invented a new and useful Improvement in Holders for Gramophone Disk Records, of which the following is a full, clear, and exact description, reference being had to the accompanying 10 drawings, which form a part of this specification.

The object of my invention is to store and transport gramophone disk records in such a way as to preserve from injury the faces 15 thereof containing the indented records, enable the records to be classified in an orderly manner, and permit ready and convenient access to any desired record.

The invention consists in a holder having 20 compartments for containing any desired number of records, the holder being constructed and arranged substantially as hereinafter set forth.

In the drawings, which illustrate a preferred embodiment of my invention: Figure 1 is a plan view of a sheet of the material of which the holder is composed, said sheet being cut away preparatory to folding and pasting. Fig. 2 is a view of the completed 30 holder before the several units thereof are folded together. Fig. 3 is a perspective view of the completed holder.

Any suitable material, such as heavy sheet paper, may be used in the manufacture of 35 the holder. The sheet is then indented as shown in Fig. 1, by means of a cutting die or otherwise, to form a solid longitudinal central portion or body *a* and side portions. Each side portion has a series of orifices or 40 indentations *c*, each of the shape of an incomplete circle, and a series of indentations *d*, each having one edge straight and one edge curved and having its greatest width a short distance from the mouth of the indentation. 45 The indentations *c* and *d* alternate with each other, and the indentations *c* or *d* of one side portion are respectively opposite the indentations *c* and *d* of the other side portion.

The sheet is scored longitudinally along 50 the lines *e*, which divide the central portion from the two side portions. The paper is also scored transversely along the lines *f*, each of which connects the meeting point of the two edges of an indentation *d* of one side 55 section with the meeting point of the two edges of the opposite indentation *d* of the

other side section. The indentations *d* extend to approximately the scoring line *e*, while the inner edge of the indentations *c* are some distance outside the scoring line *e*. The 60 scoring lines *f* divide the sheet into its component units. The indentations *d* divide the side portions into flaps *b* and *b'*—a pair for each unit.

The combined width of the two side sections is greater than the width of the central section, so that, when the side flaps of each unit are folded over upon the central section, they will overlap each other, as shown in Fig. 2. An adhesive substance is applied to 70 the surface of the two flaps of each unit along the edge thereof adjoining the straight surface of the indentation *d*, as shown by the surface shading *g*. An adhesive substance is also applied along the outer edge of the side 75 flap *b'* of each unit, as shown by the shaded surface *h*. The side flap *b* of each unit is then bent over, on one scoring line *e*, upon the face of the central portion of the unit. The other side flap *b'* is then bent over, on the 80 other scoring line *e*, upon the face of the side flap *b*. The gummed surface of the flaps *b* adhere to the opposing surface of the central portion *a*, while the gummed surface of the flaps *b'* adhere to the opposing surfaces 85 of the central portion *a* and flaps *b*. There is thus formed a unitary series of receptacles, each receptacle being open along the edge thereof adjoining the closed edge of the adjacent receptacle. Each receptacle is made 90 of a size suitable for the particular size of disks which it is intended to receive. The circular opening formed by the indentations *c, c*, of the flaps *b, b'*, is of a size approximately 95 corresponding to the size of the circular central part of a disk, on which central part, as is well known, the record is not formed, but which contains, among other data, the title of the musical selection recorded on the face of the disk outside of and concentric with, the 100 said circular central part. The holder is then folded on the lines *f* in such manner that two adjoining units face each other, thus forming a book-like holder having receptacles opening to receive the disks along one of the edges, 105 of the holder, as shown in Fig. 3.

After the records are inserted into the holder, and it is desired to extract a particular record therefrom, the holder may be manipulated in a manner corresponding to 110 the turning over of the leaves of a book. The title of the records are exposed through the

circular openings formed in the several compartments, enabling the particular record desired to be readily located. The central portion is prolonged beyond one of the end 5 units to form a flap *i*, which, when the folder is closed, is folded over the opposite end unit, thereby closing the edge of the holder through which the records are inserted and withdrawn.

10 Having now fully described my invention, what I claim and desire to protect by Letters Patent is:

A holder for gramophone record disks comprising a longitudinal central portion of 15 uniform width and two side portions, each side portion having a series of orifices extending inwardly from its edges, each orifice being of the shape of an incomplete circle and of less depth than the width of such portion, and having also a series of indentations 20

extending inwardly from the edge of such side portion and of a depth substantially equal to the width of such side portion, the indentations and orifices of each side portion being arranged alternately, and the indentations and orifices of opposite side portions being respectively oppositely arranged, said side portions being folded over upon the central portion and secured together at their adjacent edges and secured to the central portion along one of the two edges formed by each indentation, substantially as described. 25

In testimony of which invention, I have hereunto set my hand, at Philadelphia, on this 18th day of September, 1906. 30

CHARLIE H. DOUGLASS.
